United States Patent Office

Des. 215,591
Patented Oct. 14, 1969

215,591

FRONT END UNIT FOR A TRAILER

Jesse R. Birchard, Walled Lake, Clement Bondar, Beverly Hills, and Ray C. Conner, Battle Creek, Mich., assignors to Clark Equipment Company, a corporation of Delaware

Filed Sept. 20, 1968, Ser. No. 13,620

Term of patent 14 years

Int. Cl. D12—10

U.S. Cl. D14—3

FIG. 1

FIG. 2

FIG. 3

FIG. 4

FIGURE 1 is a right front quarter perspective view of a front end unit for a trailer showing our new design, the cover being over the windshield;

FIGURE 2 is a front perspective view thereof;

FIGURE 3 is a right front quarter perspective view thereof the cover being raised to expose the windshield; and

FIGURE 4 is a front perspective view thereof as shown in FIG. 3.

The portions in broken lines are shown for illustrative purposes only.

We claim:

The ornamental design of a front end unit for a trailer, as shown and described.
